(57) **CLAIM**

The ornamental design for an automobile front bumper fascia, as shown and described.

DESCRIPTION

FIG. 1 is a front perspective view of an automobile front bumper fascia showing my new design;

FIG. 2 is front view of the front bumper fascia of FIG. 1; FIG. 3 is a top view of the front bumper fascia of FIG. 1; and,

FIG. 4 is a right side elevational view of the front bumper fascia of FIG. 1, the left side elevational view being mirror symmetrical.

The broken lines are for illustrative purposes only and form no part of the claimed design.
